CEILING ACCESS OPENING AND BRACKET
THEREFOR
James M. Rallis, 412 16th St., Brooklyn 15, N.Y.
Filed Mar. 29, 1963, Ser. No. 269,098
7 Claims. (Cl. 52—497)

The present invention relates in general to an auxiliary or suspended ceiling construction and in particular to such a ceiling construction having provision for an access opening therein which is provided with a removable closure.

Ceilings of the type to which the present invention relates are formed of a plurality of tiles which are mounted in juxtaposed or abutting relation. While various attempts have heretofore been made to provide for the ready removal of one of such tiles so as to obtain an access opening through said ceiling, the prior art devices have proven to be inefficient, relatively cumbersome and relatively expensive.

In view of the foregoing, it is an object of the present invention to provide a ceiling construction of the described type which is provided with a readily closeable access opening which obviates the various objections and disadvantages of prior art devices.

It is another object of the present invention to provide a suspended ceiling construction having a highly novel closeable access opening means provided therein which is highly efficient in operation and which can be provided in the ceiling at a relatively low cost.

It is a further object of the present invention to provide a suspended or auxiliary ceiling of the described type which is provided with a closeable access opening defining means which is economical to manufacture, to mount in position and which presents a highly attractive and decorative appearance.

Other and further objects and advantages of the present invention will be readily apparent to those skilled in the art from a consideration of the following specification taken in connection with the appended drawings which illustrate the best mode presently contemplated for carrying out the invention.

In the drawings:

FIGURE 1 is a fragmentary exploded view partially in section of a suspended ceiling construction provided with means which define a readily closeable access opening therein pursuant to the present invention;

FIGURE 2 is a fragmentary sectional view through that portion of the suspended ceiling construction which is provided with the closeable access opening means pursuant to the present invention;

FIGURE 3 is a view similar to FIGURE 2 and illustrates a suspended ceiling construction provided with a plurality of closeable access opening means pursuant to the present invention;

FIGURE 4 is a perspective view of a removable tile pursuant to the present invention which is removed from the suspended ceiling construction to define the access opening;

FIGURE 5 is a top plan view of the tile illustrated in FIGURE 4 with a portion broken away;

FIGURE 6 is an exploded perspective view of a bracket or holder assembly for the access opening defining means pursuant to the present invention, the holder being illustrated as mounted in a channel or Z bar;

FIGURE 7 is a perspective exploded view of a modified form of holder or bracket assembly;

FIGURE 8 is a perspective view of the bracket or holder illustrated in FIGURE 6;

FIGURE 8a is a sectional view showing the bracket of FIGURES 6 and 8 installed; and

2

FIGURE 9 is a bottom plan view of a suspended ceiling construction having a closeable opening means defined therein pursuant to the present invention.

Referring now to the drawings in detail, a suspended ceiling construction 10 pursuant to the present invention includes a plurality of square tiles 12 of conventional construction. The tiles 12 are each provided with a continuous peripheral groove which is defined therein. As best shown in FIGURES 1 and 2, the lower peripheral side portions 16 of the tiles 12 extend outwardly for a greater distance than the upper peripheral side portions 18. As is well known to those skilled in the art, the set-back conformation of the upper portions relative to the lower portions permits the sides of the tiles 12 to be readily mounted on adjacent supporting channel or Z bars 20.

As best shown in FIGURES 1, 2 and 6, each channel or Z bar 20 which is preferably formed from suitable sheet metal, comprises a vertical wall 22 which is provided at the upper end thereof with the lateral flange 24 which extends from one side of the wall 22. Inwardly of the free longitudinal marginal edge 26 thereof the flange 24 is provided with a depressed portion 28 which extends parallel to the adjacent marginal edge 26. It will be understood that each channel member 20 is preferably formed of a single strip of sheet metal and in addition to the flange 24 which is provided preferably by bending at the upper end of the vertical wall 22, is provided also with a flange 30 which is formed by bending and doubling the strip upon itself at the lower end of the vertical wall 22 so that the double layer flange 30 extends from the wall 22 in a direction opposite to the direction of the upper flange 24. The material of the strip from which the channel member 20 is formed continues laterally of the wall 22 in the same direction as the upper flange 24 so as to define a single layer flange 32 which underlies and is spaced from the upper flange 24. The free longitudinal marginal edge of the flange 32 is bent upon itself to define a bead 34 which is spaced laterally from the wall 22. It will be readily apparent that the vertical wall 22 provided with an upper flange 24 and a lower flange 32 both extending in the same direction therefrom defines a channel construction. The flanges 30 and 32 respectively fit in opposed grooves 14 of the abutting sides of adjacent tiles 12 as will be apparent from FIGURE 9 and as is well known in the art.

In order to mount the suspended ceiling construction 10 from the overlying permanent ceiling 36, the Z bars 20 are mounted on the lower surface of the ceiling 36 by means of leaf springs 38. Each leaf spring 38 is provided with a central body portion 40 and with opposite end portions 42 and 44 which are bent upwardly from the body portion 40. An aperture 46 is defined in the body portion 40. The leaf spring 38 is secured on the lower surface of the main ceiling 36 by means of a screw or bolt 48 which passes through the aperture 46 and is threaded into the main ceiling 36. In order to mount the Z bars 20 on the lower surface of the ceiling 36, the upwardly bent end 42 of the spring 38 is engaged under the upper flange 24 in abutment with the depressed portion 28 thereof as best shown in FIGURE 2 so that the depression 28 defines a detent for the free marginal edge of the end portion 42. It will be readily apparent that as the screw 48 is threaded into the ceiling 36 the spring 38 will be stressed so as to retain the Z members or bars 20 in engagement with the main ceiling 36. It will be understood that a sufficient number of springs 38 are mounted in spaced relation longitudinally of each member 20 to provide for the adequate securing of the latter to the undersurface of the main ceiling 36.

From the foregoing, it will be apparent that a suspend-

ed ceiling 10 is defined by means of the tiles 12 which are mounted by the lower flanges 30 and 32 of the Z bars 20, the latter being engaged against the undersurface of the main ceiling 36 by the engagement of the leaf springs 38 with the upper flange 24 of the Z bar. The distance between the upper ceiling 36 and the suspended ceiling 10 depends upon the longitudinal dimension of the wall 22. In order to secure the ceiling 10 to the walls 50 of the building, the latter are provided with channels 52 secured thereto as by the screws 54. The channels engage the outer sides of the end tiles 12 so as to support the end tiles of the ceiling construction 10 in position.

Pursuant to a highly novel aspect of the present invention, provision is made for obtaining access to the area between the suspended ceiling 10 and the main ceiling 36. For this purpose, the tiles 16 are formed into modified tiles 56. The tiles 56 are in all respects similar to the tiles 12 except that the upper peripheral portion 18 along one marginal side edge thereof are broken away or removed as shown in broken line in FIGURE 1 so that along said one marginal edge thereof from which the upper peripheral portion 18 has been removed the modified tile 56 has only the lower peripheral portion or kerf of the tile 12 which remaining portion is also designated by the reference numeral 16. The removal of the upper portion 18 provides a right angular step 58 at the marginal edge from which said portion 18 has been removed. Said right angular step 58 is defined by the upper surface 60 of the underlying kerf or lower peripheral portion 16 and by the adjacent vertical surface 62 which rises upwardly from the surface 60 and which was defined by the removal of the upper peripheral portion 58. In addition to the removal of said one upper peripheral portion 18 from the tile 12 to form the modified tile 56, there is also provided in the latter an aperture 64 adjacent or inwardly of the right angular step 58 which extends completely through the modified tile 56. Consequently, it will be understood that except for the removal of one of the upper peripheral portions 18 and the formation of an aperture 64 the tile 56 is in all other respects similar to the tile 12. In addition, it will be understood that along its marginal side edge in opposition to the marginal side edge in which there is defined the right angular step 58, the tile 56 is mounted in the same manner as previously described in connection with the tiles 12, namely by the insertion of the double layer flange 30 of the Z bar 20 into the peripheral groove 14 in the opposing side marginal edge as shown for example in FIGURE 3 which shows an intermediate tile 56 having along its right peripheral edge viewing the figure a groove 14 in which the double layer flange 30 is inserted.

As previously explained, it will be understood that in connection with a normal tile 12 the single thickness flange 32 of the Z bar 20 is insertable into the peripheral groove 14 thereof while the double thickness flange 30 of the Z bar is inserted into the adjacent groove 14 of an adjacent tile 12. However, with the removal of the upper peripheral extension 18 from one marginal edge of the modified tile 56, it will be apparent that the tile 56 can no longer be supported along its modified marginal edge by means of the single flange 32 or by means of the double flange 30 since the groove 14 is no longer present at said modified edge. For this purpose, and pursuant to a highly novel feature of the present invention there is provided a bracket or holder assembly 66 for mounting a tile 56 along the marginal edge thereof which is provided with the right angular step 58. As best shown in FIGURES 6 and 8, the bracket or holder assembly 66 comprises a bracket 68, a bolt 70, a nut 72 and a washer cap 74 which is illustrated in FIGURES 1 and 2. The bracket 68 is preferably formed of a strip of sheet metal which is bent or formed into a substantially right angled configuration. The bracket 68 comprises a vertical arm 76 and a horizontal arm 78 which

is in substantial right angular relation to the vertical arm 76. Between the arms 76 and 78, there is defined a U-shaped bend 80 by means of which the arm 78 is stepped upwardly relative to the bottom of arm 76. It will be understood that the U bend can be opened as shown in FIGURE 8 or that it can be closed as for example by moving together the opposing portions of the U bend. At the upper or free end thereof the vertical arm 76 is provided with an inwardly directed flange 82 which is bent in the same direction as the direction in which the arm 78 extends away from the arm 76. The arm 76 is provided with an aperture 85 and the arm 78 is provided with an aperture 86. In order to mount a modified tile 56 along the marginal edge thereof which is provided with the right angular step 58, the bracket 68 is mounted in a Z bar 20 in the manner illustrated in FIGURE 6. More specifically and as best shown therein, the outer surface of the vertical arm 76 abuts the adjacent surface of the wall 22 of the Z bar with the flange 82 of the holder disposed in engagement with the lower surface of the flange 24 at the upper end of the wall 22. At its upper end, the holder 68 is retained in position within the Z bar by engagement of the marginal edge 84 of flange 82 with the detent 28 defined in the flange 24 of the Z bar. The U bend 80 is seated on the upper surface of the single lower flange 32 of the Z bar and it will be noted that the U bend is engaged by the bead 34 which serves as a detent for the holder along the lower portion thereof. In this connection, it will be understood that the bead 34 does not constitute an essential feature of the present invention. It may be desirable where the bead 34 is not utilized, to provide an aperture in the wall 22 in registry with the aperture 85 in the arm 76 of the holder for securing the holder to the Z bar by means of a bolt extending through said apertures. With the holder 68 mounted in the Z bar as illustrated in FIGURE 6, the arm 76 will then overlie the tile 56 in the manner shown for example in FIGURE 2 which illustrates a modified form of holder designated by the reference numeral 90 which is hereinafter described in detail. With the arm 78 overlying the tile 56, the aperture 86 therein will be in registry with the aperture 64 in the tile and the flange 32 of the Z bar 20 will extend into the right angular step 58 of the tile 56 as illustrated in FIGURE 2. The tile may then be readily releasably secured to the holder 68 by inserting the bolt 72 in an enlarged upper portion 92 of the aperture 64 as shown in FIGURE 2. The bolt 70 may then be readily threaded through the aperture 86 in the holder and through the bolt 72 so as to extend through and outwardly from the aperture 64. At the bottom or lower surface of the tile 56, the washer cap 74 is engaged in threaded relation on to the exposed portion of the bolt 70.

A modified form of bracket assembly 94 utilizing the modified holder or bracket 90 is illustrated in FIGURE 7. In addition to the holder or bracket 90, the bracket assembly 94 also includes the bolt 70, the nut 72 and the washer cap 74. The holder 90 is also formed of a strip of sheet metal which is bent upon itself to define a substantially right angular configuration. As here shown, the holder 90 is provided with a vertical arm 96 and with a horizontal arm 98 which is in substantially right angular relation to the vertical arm 96. A U bend 100 is interposed at the junction between the arms 96 and 98 and serves to step up the arm 98 relative to the bottom of the arm 96, the same manner as in connection with the relationship between the arms 76 and 78 of the holder 68 and the U bend 80 therebetween. At the upper end thereof the arm 96 is provided with an inwardly bent flange portion 102 which extends in the same direction as the direction in which the arm 98 extends away from the arm 96. The holder 90 also includes a horizontal flange 104 which overlies and is parallel to the underlying horizontal arm 98. An integral angular portion 106 extends between the flange portion 102 and the

flange 104. An aperture 108 is defined in the flange 104 and an underlying aperture in registry therewith as indicated at 110 is defined in the underlying horizontal arm 98.

The holder 90 is mounted in the Z bar 20 as best shown in FIGURES 1 and 2. In this connection, it will be noted that the holder 90 is substantially similar to the holder 68 in that the holder 90 contains the various parts of the holder 68, except the aperture 84 of the latter and in addition is provided with the additional lower flange 104 and with the angular portion 106 which extends from the upper flange portion 102 to the lower flange 104 of the holder 90. Consequently, the holder 90 is mounted in the Z bar 20 in substantially the same manner as the holder 68. More specifically, the upper flange 102 of the holder 90 is seated between the depressed detent 28 in the upper flange 24 of the Z bar and the upper end of the vertical wall 22. The vertical arm 96 of the holder 94 engages the inner surface of the vertical wall 22 and the U bend 100 thereof is seated on the lower single flange 32 of the Z bar being engaged with the bead 34 as best shown in FIGURE 2. As previously indicated, it will be understood that the bead 34 is not an essential feature of the present invention and furthermore that the U bend 100 can be open as shown or it can be closed by pinching together the opposing vertical portions thereof. The horizontal arm 98 is engaged on the upper surface of the modified tile 56, the single lower flange 32 of the Z bar being seated within the right angular step of the tile 56 as best shown in FIGURE 2. The nut 72 is inserted into the enlarged upper portion 92 of the aperture 64 and the apertures 108 and 110 being in registry and being disposed in registry with the underlying aperture in the tile, the bolt 70 is then threaded through the aligned apertures and through the nut 72 so as to project from the lower surface of the tile 56. The washer cap 74 is then threaded onto the projecting portion of the bolt 70.

When utilizing either the bracket or holder 68 or the bracket or holder 90, the tile 56 which is mounted thereby may readily and expeditiously be removed from the ceiling 10 so as to obtain access to the space between the drop ceiling 10 and the upper ceiling 36. This is accomplished in a very simple manner by merely removing the washer nut 74 from the bolt 70 so as to release the tile 56 from the associated holder. The tile may then be tilted downwardly from the ceiling 10 so as to disengage the opposed marginal side thereof from the double layer flange 30 of the adjacent Z bar which extends into the groove 14 which is defined in the marginal edge of the tile 56 opposite that provided with the right angular step 60. In either case, whether using the holder 68 or the holder 90 it will be readily apparent that there is provided a means for readily removing one of the tiles of the ceiling 10 for obtaining access to the space between the drop ceiling and the permanent ceiling.

It will be readily apparent that the arrangement of the foregoing holder assemblies and the utilization of a modified tile 56 provides a relatively inexpensive means for obtaining a removable access opening closure means for a drop ceiling which is less expensive than the arrangements proposed in the prior art. Moreover the holder devices of the present invention provide better support for the removable tile 56 than is possible with prior art constructions because the holders of the present invention are mounted within the channel of the Z bar defined by its upper flange 24, its lower flange 32 and the vertical wall 22 extending therebetween. Moreover, it will be noted that in each of the holders of the present invention, the horizontal arm which extends therefrom abuts the upper surface of the modified tile 56 and is secured thereto by means of the bolt 70. As a result, there is less stress provided on the channel 22 and there is a slight resilience provided by means of the holder

arrangement of the present invention which minimizes the stress or tension to which the Z bar 20 is subjected.

In view of the foregoing, it will be apparent that pursuant to the present invention there has been provided a highly novel and efficient arrangement for providing a removable access opening closure in a drop ceiling of the type which is described. It will be understood that various changes and modifications may be made therein without however departing from the inventive concept thereof as set forth in the appended claims.

I claim:

1. In a suspended tile ceiling construction, an elongated member for supporting the tiles of said ceiling in spaced relation below a main ceiling, said member having a vertical wall provided with substantially right angled flanges at the upper and lower ends thereof which define a channel and with an additional right angled flange at said lower end which extends in a direction opposite to the lower channel defining flange, said upper flange being adapted to be secured to the main ceiling and said additional channel being adapted to support a tile, and holder means mounted within said channel for supporting a tile closure plate in said ceiling, said holder means comprising substantially right angular bracket means having a vertical body portion abutting said vertical wall, an upper substantially right angled flange means abutting the upper flange of said channel, a substantially right angled lower flange provided with aperture means defined therein for receiving a securing means whereby said holder is adapted to be releasably secured to the upper surface of the tile closure plate and a substantially reverse L-shaped bend abutting the lower flange of said channel, said bend extending between the bottom of said vertical body portion and the lower flange of said bracket means, said lower flange of said holder means being disposed between said channel defining flanges and extending laterally therefrom, said upper channel defining flange having a detent portion for retaining said upper holder flange in position, and said lower channel defining flange having a detent portion for retaining said lower holder flange in position.
2. A suspended tile ceiling construction as in claim 1, said detent portion of said lower channel defining flange being a bead defined at the free marginal edge of said lower channel defining flange.
3. In a suspended tile ceiling construction, an elongated member for supporting the tiles of said ceiling in spaced relation below a main ceiling, said member having a vertical wall provided with substantially right angled flanges at the upper and lower ends thereof which define a channel and with an additional right angled flange at said lower end which extends in a direction opposite to the lower channel defining flange, said upper flange being adapted to be secured to the main ceiling and said additional channel being adapted to support a tile, and holder means mounted within said channel for supporting a tile closure plate in said ceiling, said holder means comprising substantially right angular bracket means having a vertical body portion abutting said vertical wall, an upper substantially right angled flange means abutting the upper flange of said channel, a substantially right angled lower flange provided with aperture means defined therein for receiving a securing means whereby said holder is adapted to be releasably secured to the upper surface of the tile closure plate and a substantially reversed L-shaped bend abutting the lower flange of said channel, said bend extending between the bottom of said vertical body portion and the lower flange of said bracket means, said lower flange of said holder means being disposed between said channel defining flanges and extending laterally therefrom, said upper channel defining flange having a detent portion for retaining said upper holder flange in position, and said lower channel defining flange having a detent portion for retaining said lower flange in position, said bracket means having a flange extension ex-

tending downwardly from the upper flange of said bracket means and having a portion overlying in parallel relation, the lower flange of said bracket means, said overlying portion having aperture means defined therein in registry with said first mentioned aperture means for receiving the securing means.

4. A suspended tile ceiling construction as in claim 3, said detent portion of said upper channel defining flange engaging the junction of the upper flange of said bracket means and said flange extension.

5. A suspended tile construction as in claim 3, and a threaded bolt extending through said registered apertures for securement to the tile closure plate, and a capped washer for engagement with the free end of said bolt projecting from the bottom of the tile closure plate.

6. A bracket for supporting a closure plate in a suspended tile ceiling carried by flanged channel members, said bracket comprising a vertical body portion, substantially right angled flange means at the upper end of said body portion, a substantially reversed L-shaped bend at the lower end of said body portion, a substantially right angled lower flange extending from said L-shaped bend in the same direction as said flange means and laterally thereof, and a flange extension extending downwardly from said upper end flange means, said flange extension having a flange portion in overlying parallel abutting relation with said lower flange and an oblique

portion extending downwardly from said upper end flange means to said overlying flange portion.

7. A bracket as in claim 6, and registering apertures defined in said overlying flange portion and in said lower flange.
